(57) CLAIM

The ornamental design for a shave preparation package, as shown and described.

DESCRIPTION

FIG. 1 is a perspective view of a design for a shave preparation package of the present invention including a window showing a blue-colored shave preparation in the package;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a design for a shave preparation package according to a second embodiment of the present invention including a window showing a shave preparation in the package;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The dash broken lines are directed to the environment and are for illustrative purposes only and form no part of the claimed design.
